UNITED STATES PATENT OFFICE

WILLIAM E. McCULLOUGH, OF KENOSHA, WISCONSIN, ASSIGNOR TO SIMMONS COMPANY, OF KENOSHA, WISCONSIN, A CORPORATION OF DELAWARE

KNOB

Application filed August 13, 1928. Serial No. 299,173.

My invention relates to a novel type of molded knob of such type as is commonly used in connection with dresser and bureau drawers and for similar purposes.

5 One of the objects of my invention is to provide a simple two-piece knob whose assembly is such that the method employed in putting together the two pieces that constitute the knob at the same time serve to fasten and
10 position the same to the drawer, desk or other article of furniture to which it may be attached.

A further object of my invention is to provide a knob molded of thermoplastic material consisting of a main body portion and an insert, which latter is internally threaded, each of these parts being made, if desired, of different color and design so that by keeping in stock a plurality of different colored parts any desired combination may readily be made up.

Further objects of my invention will appear in connection with the description and the drawing which forms a part of the present application, in which drawing

Figure 1 is a side elevation of the knob showing its attachment to a flat surface such as the front of a bureau drawer;

Fig. 2 is a plan view thereof;

30 Fig. 3 is a sectional view;
Fig. 4 is a front view of the main body portion with the insert removed;

Fig. 5 is a forward view of the inside surface of the insert; and

35 Fig. 6 shows a metallic yoke employed in connection with the main body portion of the knob to prevent the same from turning and becoming loosened when attached to the front of the bureau drawer.

40 As will be seen from the figures, the knob itself comprises a main body portion 10 which is made of a thermoplastic resinoid material of the nature of bakelite or the like although obviously other materials may be employed.
45 for its construction. The body portion 10 has a central opening adapted to receive the

a central opening adapted to receive the metallic screw 12. This screw is adapted to pass through an opening provided in the bureau drawer front 16 passing through the central opening of the body portion 10 and

projecting into the recessed portion 10^a thereof. There is also provided the molded insert and covering piece 11 which is provided on the inner side thereof with a threaded portion 13 having threads that engage the end of the screw 12, as is more clearly shown in the sectional view in Fig. 3.

In placing the complete knob in position three holes are drilled in the bureau drawer front 16, that is to say, a central hole to receive the screw 12 and two smaller holes 17 and 17^a which are adapted to receive the prongs 18 of the metallic yoke 19. The end of the body portion 10 is also provided with two small holes 20 and 20^a into which the prongs 18 of yoke 19 extend, thereby preventing the body portion 10 from revolving when the screw 12 is applied, as well as preventing the turning of the body portion 10 when the insert 11 is fastened to the screw 12. 700 600 650

The method of attaching the knob is as follows:

The above-mentioned holes having been provided, the yoke 19 is placed upon the screw in the position shown in Fig. 3, whereupon the screw and yoke are inserted in their respective holes, the body portion 10 being then slipped over the screw 12 so that the holes 20 and 20^a engage the ends of the prongs 18 whereupon the insert 11 is swung onto the end of the screw following which the screw is tightened by means of a screw-driver and is held until a tight connection is established. The insert 11 may be so proportioned that it slightly overhangs the body portion 10, thereby concealing the fact that the knob consists of two pieces. The insert 11 may either consist of the same type of molded material as the body portion 10 or it may equally well be made of metal. In fact the entire knob, without departing from the scope of my invention, may be made of metal. The design shown is merely an exemplification of my invention and cannot be considered a limiting feature.

The present invention has found particular application in the construction of molded resinoid furniture such as is disclosed in co-pending applications, Serial No. 293,035, filed July 16, 1928, Serial No. 293,036, filed July 16, 1928.

16, 1928, Serial No. 293,037, filed July 16, 1928.

Having thus described my invention, what I claim is:

- 5 1. In combination with the front wall of a drawer, a knob comprising a body portion adapted to lie flat against the outer surface of a drawer wall and having a central aperture therein, a frontal portion having a threaded opening therein extending nearly to the outer surface thereof, a screw passing through an opening in the drawer wall through said central opening in the body portion and fitting into a threaded opening in the frontal portion whereby said knob is attached to said drawer.
- 10 2. In combination, a panel, a knob on the front thereof comprising a body portion having a central aperture, a headed screw inserted through the panel from the back thereof and passing entirely through said aperture, a washer interposed between the head of said screw and the back surface of said panel and provided with an integral lug extending in distance from the access of said screw and in a direction longitudinal of said axis, said panel and said body portion being provided respectively for receiving and interlocking with said lug whereby rotation of said body portion relative to said panel is prevented, a closure piece fitted to a recess in said body portion and having threaded openings on the reverse side thereof, said threaded openings engaging the ends of said screw.
- 15 3. In witness whereof, I have hereunto subscribed my name.
- 20 WILLIAM E. McCULLOUGH.
